UNITED STATES PATENT OFFICE.

MAURICE J. WOHL AND HARRY HERTZBERG, OF NEW YORK, N. Y.

DESIGN FOR AN ARC-LAMP.

No. 39,565.

Specification for Design.

Patented Sept. 22, 1908.

Application filed June 16, 1908. Serial No. 438,868. Term of patent 14 years.

To all whom it may concern:

Be it known that we, MAURICE J. WOHL and HARRY HERTZBERG, citizens of the United States, and residents, respectively, of the city of New York, borough of Manhattan, county and State of New York, and of the city of New York, borough of Brooklyn, county of Kings, and State of New York, have invented a new, original, and ornamental Design for Arc-Lamps, of which the following is a specification, reference being had to the accompanying drawing, forming part thereof.

The figure is an elevation of an arc lamp, showing our new design.

The arc lamp casing comprises a cylindrical body having an ornamental outline. The lower portion of the body is provided with an outwardly flaring portion of circular cross

section and at the lower end an outwardly and downwardly flaring reflector of circular cross section is provided. The intermediary sections of the body portion of the casing are perforated, the outline of the principal perforations being miniature reproductions of the outline of the lamp. The globe of the lamp is acorn-shaped in outline, the upper portion being partially hidden by the reflector.

We claim:

The ornamental design for an arc lamp as shown and described.

MAURICE J. WOHL.
HARRY HERTZBERG.
